COIL SUPPORTING APPARATUS

Weld Morgan, Worcester, Mass., assignor to Morgan Construction Company, Worcester, Mass., a corporation of Massachusetts

Application December 10, 1941, Serial No. 422,333

9 Claims. (Cl. 242—129)

This invention relates to coil supporting apparatus, and more particularly to apparatus arranged to support annular bundles of metal rod or wire while it is being paid off to some other machine.

In the manufacture of wire it is the practice to pass metal billets through a rolling mill and form long rods of comparatively small diameter, and to coil these rods into annular bundles. Wire is produced by drawing the rods through dies, and during this process the rod bundles must be suitably supported adjacent the wire-drawing machine so that the rod will uncoil properly without snarling. By welding together the ends of the rods in successive bundles it is possible to maintain the wire-drawing machine in continuous operation until the dies become so worn as to require replacement. It has been proposed to support the bundles upon arms which project in generally radial directions from a turn-table, this latter being mounted for free rotation about a vertical axis. However, it is necessary for the operator to turn this apparatus by hand as soon as one bundle has become exhausted, and thereby bring the next bundle into the correct position for unwinding. This requires considerable watchfulness on the part of the operator, who may have charge of several machines, and there may be occasions when two machines will exhaust their bundles nearly simultaneously. If the operator is not present to rotate the coil support at the proper time, snarling and breakage of the rod may occur. Similar problems may be involved whenever any elongated metal product is to be paid off from a coil for further processing. As an example, bundles of wire may be used to supply stock to a machine for manufacturing springs or other wire products.

It is accordingly one object of the invention to provide an improved apparatus to support annular bundles of rod or wire in such a manner that as soon as one bundle has become exhausted the next bundle will be moved automatically into the proper pay-off position.

It is a further object of the invention to provide an improved turn-table for the support of a plurality of annular bundles of rod or wire joined by welding, the construction being such that as soon as one bundle has become exhausted the apparatus will be rotated automatically to bring the next bundle into the position previously occupied by the exhausted bundle.

With these and other objects in view, as will be apparent to those skilled in the art, the invention resides in the combination of parts set

forth in the specification and covered by the claims appended hereto.

Referring to the drawing illustrating one embodiment of the invention and in which like reference numerals indicate like parts,

Fig. 1 is a perspective view of a coil supporting apparatus; and

Fig. 2 is a fragmentary vertical section through the apparatus.

- 10 The embodiment illustrated comprises a base 10 adapted to be secured to a floor or other foundation. From this base a column 11 extends vertically upward, this column preferably being hollow in order to afford adequate strength without excess weight. The column 11 is surrounded by a hollow vertical member or upright 12 which is closed at its upper end by a plate 14, this plate resting on a ball 15 forming a pivot bearing on the upper end of the column 11. Thus the member 12 is supported for free rotation about a vertical axis.

In order to support the bundles of rods to be paid off in a desired manner, two arms 17 extend in generally radial directions from opposite sides of the member 12. These arms are located appreciably below the upper end of the member 12 and they preferably slope upwardly and outwardly at a slight angle. Beneath each of the arms 17 there is provided a lower arm 18, these lower arms extending radially from the member 12 adjacent the lower end thereof. Two annular rod bundles A and B may be suspended from the upper arms 17, with the bottom portions of the bundles passing beneath the lower arms 18. The usual clicker bars 19 are pivotally connected to the upper portion of the member 12, above the upper arms 17, these clicker bars resting upon the rod bundles to aid in the orderly release of the convolutions therefrom.

- 40 It will now be apparent that with bundle A positioned as shown in Fig. 1, rod may be withdrawn therefrom by a wire-drawing machine or other apparatus (not shown). While this is taking place, the tall end of the rod in bundle A 45 may be welded to the front end of the rod in bundle B to provide a strand S which connects the two bundles. If, upon exhaustion of the rod from bundle A, the member 12 is rotated 180 degrees to bring bundle B into the position formerly occupied by bundle A, the paying off of the rod may continue without interruption.

The present invention provides means whereby this rotation of the turn-table will be brought about automatically without the necessity of manual assistance. For this purpose I provide

means to support the connecting strand S at a considerable distance from the axis of the turn-table, so that the desired rotation will be effected through the medium of tension applied to this strand upon exhaustion of the first bundle A. In the particular embodiment illustrated this support is obtained by providing two rectangular brackets or frames 21 which extend from the member 12 in opposite radial directions intermediate the arms 17, each bracket having a hook or finger 22 thereon extending in a generally outward radial direction and preferably with a slight upward slope.

The operation of the invention will now be apparent from the above disclosure. While the rod bundle A is being uncoiled, a second bundle B will be placed upon the opposite arm 17, and the ends of the two rods will be welded together to provide a connecting strand S which will be placed upon the adjacent hook 22. The operator can then leave the machine, for as soon as the first bundle A is exhausted, tension will be applied to the strand S, and this tension will produce a considerable torque because of the large moment arm afforded by the bracket 21. Consequently the entire turn-table 12 with its arms 17 and 18 will start to rotate. After the parts have turned through an appreciable angle the strand S will slip outwardly off the finger 22, but the momentum of the table and coil, aided by the continued pull of the wire, will cause the rotation to proceed until the bundle B has reached substantially the position formerly occupied by the bundle A. Before the bundle B has been exhausted, the operator will return to mount a third bundle on the empty arm 17 and connect the two bundles by a welded strand, which he will loop over the adjacent finger 22. Thus the uncoiling may proceed continuously, and there is no need for the operator to be present at the exact time when rotation of the table is required, since this will take place automatically.

Having thus described my invention, what I claim as new and desire to secure by Letters Patent is:

1. Coil supporting apparatus comprising a turn-table mounted for rotation about a vertical axis, means on the turn-table to support a plurality of annular bundles of rod or wire in positions spaced about the axis, the bundles being arranged to be uncoiled one at a time and successive bundles being joined by a connecting strand, and means on the turn-table to support the said connecting strand at a considerable distance from the axis so that upon exhaustion of one bundle the resultant tension in the said connecting strand will cause the turntable to rotate and bring the next bundle into the proper position to be uncoiled.

2. Coil supporting apparatus comprising a turn-table mounted for rotation about a vertical axis, means on the turn-table to support a plurality of annular bundles of rod or wire in positions spaced about the axis and with the axes of the bundles extending in generally horizontal directions outwardly from the axis of the turn-table, the bundles being arranged to be uncoiled one at a time and successive bundles being joined by a connecting strand, and means on the turn-table to support the said connecting strand at a considerable distance from the axis of the turn-table so that upon exhaustion of one bundle the resultant tension in the said connecting strand will cause the turn-table to rotate and bring the

next bundle into the proper position to be uncoiled.

3. Coil supporting apparatus comprising a turn-table mounted for rotation about a vertical axis, a plurality of arms projecting in generally radial directions from the turn-table and spaced about the axis thereof so that an annular bundle of rod or wire may be suspended from each arm, the bundles being arranged to be uncoiled one at a time and successive bundles being joined by a connecting strand, and hooks mounted on the turn-table at a considerable distance from its axis and intermediate the arms, each hook being arranged to support the adjacent connecting strand and thereby ensure automatic rotation of the turn-table upon exhaustion of each bundle.

4. Coil supporting apparatus comprising a turn-table mounted for rotation about a vertical axis, a plurality of arms projecting in generally radial directions from the turn-table and spaced about the axis thereof so that an annular bundle of rod or wire may be suspended from each arm, the bundles being arranged to be uncoiled one at a time and successive bundles being joined by a connecting strand, frames extending in generally radial directions from the turn-table and intermediate the arms, and an outwardly open hook on each frame arranged to support the adjacent connecting strand and thereby ensure automatic rotation of the turn-table upon exhaustion of each bundle.

5. Coil supporting apparatus comprising a turn-table mounted for rotation about a vertical axis, means on the turn-table to support two annular bundles of rod or wire in diametrically opposed positions for uncoiling one at a time, the bundles being joined by a connecting strand, and means on the turn-table to support the said connecting strand at a considerable distance from the axis so that upon exhaustion of one bundle the resultant tension in the said connecting strand will cause the turn-table to rotate and bring the other bundle into the proper position to be uncoiled.

6. Coil supporting apparatus comprising a turn-table mounted for rotation about a vertical axis, means on the turn-table to support two annular bundles of rod or wire in diametrically opposed positions and with the axes of the bundles extending in generally horizontal directions outwardly from the axis of the turn-table, the bundles being arranged to be uncoiled one at a time and being joined by a connecting strand, and means on the turn-table to support the said connecting strand at a considerable distance from the axis of the turn-table so that upon exhaustion of one bundle the resultant tension in the said connecting strand will cause the turn-table to rotate and bring the other bundle into the proper position to be uncoiled.

7. Coil supporting apparatus comprising a turn-table mounted for rotation about a vertical axis, two arms projecting from the turn-table in diametrically opposed and generally radial directions so that an annular bundle of rod or wire may be suspended from each arm, the bundles being arranged to be uncoiled one at a time and being joined by a connecting strand, and a hook mounted on the turn-table at a considerable distance from its axis and intermediate the arms in position to support the said connecting strand and thereby ensure automatic rotation of the turn-table upon exhaustion of each bundle.

8. Coil supporting apparatus comprising a turn-table mounted for rotation about a verti-

cal axis, two arms projecting from the turn-table in diametrically opposed and generally radial directions so that an annular bundle of rod or wire may be suspended from each arm, the bundles being arranged to be uncoiled one at a time and being joined by a connecting strand, and two hooks mounted on the turn-table in diametrically opposed positions at a considerable distance from its axis and intermediate the arms, one or the other of the hooks being in position to support the said connecting strand and thereby ensure automatic rotation of the turn-table upon exhaustion of each bundle.

9. Coil supporting apparatus comprising a turn-table mounted for rotation about a vertical 15

axis, two arms projecting from the turn-table in diametrically opposed and generally radial directions so that an annular bundle of rod or wire may be suspended from each arm, the bundles being arranged to be uncoiled one at a time and being joined by a connecting strand, two frames mounted on the turn-table in diametrically opposed positions intermediate the arms and extending in generally radial directions, and an outwardly open hook on each frame, one or the other of the hooks being in position to support the said connecting strand and thereby ensure automatic rotation of the turn-table upon exhaustion of each bundle.
